(57) **CLAIM**

The ornamental design for a wagon canopy, as shown and described.

DESCRIPTION

FIG. 1 is a perspective view of the wagon canopy;

FIG. 2 is a front end elevational view of the wagon canopy, the opposite end of which is identical;

FIG. 3 is a right side elevational view of the wagon canopy, the opposite side of which is identical;

FIG. 4 is a top plan view of the wagon canopy;

FIG. 5 is a bottom plan view of the wagon canopy; and,

FIG. 6 is a perspective view of the wagon canopy as installed on a wagon.

The broken lines are for illustrative purposes only and form no part of the claimed design.

1 Claim, 4 Drawing Sheets

FIG. 1

FIG. 2

FIG. 3

FIG. 4**FIG. 5**

FIG. 6
